UNITED STATES PATENT OFFICE.

JOSEPH N. BROWN, OF FARWELL, MICHIGAN, ASSIGNOR OF ONE-HALF
TO FRANK E. PRESLEY, OF SAME PLACE.

HAND WEIGHING-TRUCK.

SPECIFICATION forming part of Letters Patent No. 432,597, dated July 22, 1890.

Application filed October 25, 1889. Serial No. 328,148. (No model.)

To all whom it may concern:

Be it known that I, JOSEPH N. BROWN, a citizen of the United States, residing at Farwell, in the county of Clare and State of Michigan, have invented certain new and useful Improvements in Hand Weighing-Trucks; and I do hereby declare the following to be a full, clear, and exact description of the invention, such as will enable others skilled in the art to which it appertains to make and use the same.

This invention relates to weighing hand-trucks; and it consists in certain improvements in the construction of the same, as hereinafter described and claimed.

In the accompanying drawings, Figure 1 is a plan view of a hand-truck provided with my improvements, portions of the platform being broken away. Fig. 2 is a section taken on line *x x* of Fig. 1. Fig. 3 represents a rear end view of the truck. Fig. 4 is an interior view of the register, the dial being mostly broken away. Fig. 5 is a section taken on line *y y* of Fig. 4.

The frame of the truck consists of the side bars *A*, which are extended to form the handles *B*, and the cross-bars *a*, *a'*, and *a''*. A central rod *b* is fixed to or in the said cross-bars, and on said rod are placed the springs *d*. Two other rods *d'* *d''* are fixed to the bars *a* *a''*, and have springs placed on them, as shown. The platform *C* of the truck is loosely connected with the frame by means of the perforated angle-irons *e*, which are fastened to the lower side of the platform and are loosely connected with the rods *b* *d'* *d''*, which are passed through perforations in said angle-irons. Grooved wheels *e* are connected with the side bars of the frame and are in position to move on tracks *f*, which are fastened to the platform *C*.

D indicates a lever, which is pivoted to the cross-bar *a'*, and is provided with a projection *g*, for connection with a stop *k* on the lower side of the platform when the weighing apparatus is not in use.

h indicates a perforated block, which is placed on the central rod *b* just below the cross-bar *a*, the said block resting on a spring *d* and having vertical movement on said rod.

Two levers *i* are pivoted to the side bars *A*, one being secured to each side bar and extending across the frame nearly to the opposite bar *A*. These levers *i* are connected by the short strips *n* with the platform *C* on the under side, and are provided at their free ends with hooks which are connected by rods *m* with the movable block *h*.

E indicates the casing of a registering device, which is secured to a curved bar *F* and is provided with a dial on which move the indicating-hands *o*. Within the casing is mounted a central shaft *p*, which carries a ratchet-wheel *q*, the hub of which is provided with ratchet-teeth *r*. A pinion *s* is loose on the shaft *p*, and a sleeve *u* on said shaft extends forward from said pinion and carries one of the indicating-hands *o*, the other hand being carried by the shaft *p*. The long hand indicates on the dial the weight of a load and the other the number of loads weighed. A segment-gear *t* is pivoted in position to engage the pinion *s*, and is connected by a rod *u'* with a slotted bar *w*, which is connected at *v* with a cross-bar of the frame, the other end of said bar *w* being connected with the block *h*. A pawl *s'*, which is connected with the pinion *s*, engages the shaft *p* by its connection with the ratchet-teeth *r*, and a spring-pawl *y*, connecting with the ratchet-wheel *q*, prevents a backward movement of the shaft *p*. The pawls *s'* and *y* may be raised from the teeth *r* on the hub of wheel *q* and pinion *s* by means of a spring-rod *w'*, a button *z* on the outer end of said rod being pressed.

I claim—

1. In a weighing-truck, the combination, with a frame and a movable platform, of a central rod, which is fixed to said frame and loosely connected with said platform, the spring on said rod, a perforated block placed loosely on said rod and supported by said spring, two levers which are pivoted to the side bars of the frame, the strips which connect the said levers with the platform, two rods which connect the free ends of said levers with said perforated block and a registering device, a slotted bar *w*, which is pivoted to the frame and connected with said perforated block, and the rod which connects

the registering mechanism with the slotted bar w , substantially as and for the purposes described.

2. The combination, with the platform C and the registering mechanism, of the connecting mechanism consisting of the pivoted rod w' , the pivoted slotted bar w , the movable block h , the pivoted rods $m m$, the levers

$i i$, and the pivoted strips $n n$, as and for the purpose set forth.

In testimony whereof I have affixed my signature in presence of two witnesses.

JOSEPH N. BROWN.
